UNITED STATES PATENT OFFICE.

CAMIILLE PULCHER, OF MURPHYSBOROUGH, ILLINOIS.

CLOTH-MEASURING DEVICE.

SPECIFICATION forming part of Letters Patent No. 601,277, dated March 29, 1898.

Application filed August 30, 1897. Serial No. 650,042. (No model.)

To all whom it may concern:

Be it known that I, CAMIELLE PULCHER, a citizen of the United States, residing at Murphysborough, in the county of Jackson, State of Illinois, have invented certain new and useful Improvements in Measuring Devices, of which the following is a specification, reference being had therein to the accompanying drawings.

10 This invention relates to measuring devices, and more particularly to a lineal measure arranged to compute the cost of a quantity of the article for sale.

15 The invention has for its object to provide such a measure having a series of price-sheets so arranged that any one of the same may be brought into use, so as to compute the cost of the goods sold as the measuring operation is performed.

20 It has for a further object to arrange the sheets in book form, so that the same can be conveniently applied to a counter and the dry goods or other articles measured held upon the price-sheet.

25 Other objects and advantages of the invention will hereinafter appear in the following description and the novel features thereof will be particularly pointed out in the appended claims.

30 In the drawings, Figure 1 is a perspective of the invention applied to the edge of a counter. Fig. 2 is a plan view of the device, the top cover open; and Fig. 3 is a vertical section through the counter with my device applied thereto.

Like letters of reference indicate like parts throughout the several figures of the drawings.

35 The letter A designates a book composed of a series of price-sheets bound together and provided with a protecting-cover A'. These sheets may be of any desired quality of paper found preferable in use, or a suitable cloth fabric, and may be formed of any desired length. In the form of the invention illustrated in this case the sheets A are one yard in length and, as shown in Fig. 1, are divided by a series of vertical lines A² into the fractional parts of a yard or other unit of lineal measurement. Extending longitudinally of the sheet is a series of lines A³ to guide the operator in the use of the device. Adjacent

to each of the vertical lines A² is arranged a series of price-computing numerals a, reading from right to left, to indicate the price to be charged for the quantity of goods measured, while upon the back of the preceding sheet or page a reversely-arranged price-numeral a' is placed to indicate that the opposite page is for computing the cost of goods at four cents or dollars per yard. This numeral is usually arranged to face the outside of the counter where the purchaser is standing, as shown in Fig. 1.

40 The book of price-sheets may be secured to a counter D for use, for instance, by passing one edge of the rear cover thereof over the inner side of the counter to secure the same by tacks a² or other devices, while the front cover will be secured to the counter by similar tacks a³, so that the pages may be opened into a flat position and the one in use brought adjacent to the inside of the counter, where the salesman can readily place the goods upon the same for measurement. At 45 opposite ends of the book are arranged vertical guard-strips B, which in the present instance are one yard apart and are secured to the counter by fastening means b, so that the goods to be measured may be extended or stretched from one guard to the other and the edges of the price-sheet thereby protected against injury from contact with the goods. It has also been found desirable to secure a series of strips C to the counter to prevent 50 the bolt of cloth or main body of the material being measured from coming into contact with the edges of the sheets so as to injure the same. The edges of the sheets composing the book are indexed, as at A⁴, so that the salesman can readily refer to the sheet for computing the price per yard to be charged for the goods.

45 Referring now to the method of using the invention, it will be observed that the book, as shown in Fig. 2, presents the indexed edge, by means of which the salesman can refer to any desired page—for illustration, to page numbered 4, as shown in Fig. 1. The book being opened at this point, the large price-numeral "4" will be before the purchaser. If the salesman desires to measure two and three-fourths yards of goods at four cents per yard, he will first measure one yard from right

to left upon the first longitudinal line of numerals, then a second yard upon the second line of numerals, and three-fourths of a yard upon the third line of numerals. At that 5 point he will find the cost price of eleven cents. As each successive yard is measured the salesman will move the edge of the goods slightly downward to correspond with the next line of numerals. The lines A³ may ex- 10 tend beneath each line of numerals, but for the purpose of clearness of illustration have been omitted from some of the lines of numerals. Each page is arranged to measure ten yards of goods and to compute the price 15 of any less number of yards or fractions thereof. The invention is also adapted to sell goods by lineal measure for a stated price. For instance, if a purchaser desired twenty-five cents' worth of cloth at four cents per 20 yard the salesman would continue to measure the cloth until he reached the mark indicating twenty-five cents, which in the present instance would be six and one-fourth yards. Other arrangements of matter may 25 be placed upon the several price-sheets to compute the price for lineal measurement in any desired manner and the sheets may be bound or secured together and to the counter in any preferred manner or used without at- 30 tachment to a counter. It is also obvious that the guards at the opposite sides of the book may be omitted and other changes in construction and configuration of the same made without departing from the spirit of the 35 invention.

Having described my invention and set forth its merits, what I claim as new, and desire to secure by Letters Patent, is—

1. A measuring device comprising a book having cover-leaves adapted to be secured to a support, and a series of superposed sheets each having thereon longitudinally parallel indications for lineal measurement and for successively computing the prices of units and multiples of the length of said measuring device; substantially as specified. 40

2. A measuring device comprising a book having cover-sheets adapted to be secured to a support, and a series of price-sheets having upon one face indications for lineal measurement and upon the reverse face with price-numerals upon each sheet preceding the one having said computations thereon; substantially as specified. 45

3. In a measuring device, a series of sheets secured together and provided with indications corresponding with units of lineal measurement and for computing the cost thereof, a cover secured to said sheets, and guards secured to a support at opposite ends of the sheets, substantially as specified. 55

4. In a measuring device, a series of price-sheets having thereon indications for lineal measurement and for computing the prices of units of said measurement, said sheets being provided with indexed edges, and price-numerals arranged upon the back of each sheet preceding the one having said price computation thereon, substantially as specified. 65

In testimony whereof I affix my signature 70 in presence of two witnesses.

CAMIELLE PULCHER.
